UNITED STATES PATENT OFFICE.

JAMES B. BRYAN, OF HUTCHINSON, KANSAS.

VALVE-SEATING TOOL.

Application filed February 7, 1923. Serial No. 317,558.

To all whom it may concern:

Be it known that I, JAMES B. BRYAN, a citizen of the United States, residing at Hutchinson, in the county of Reno and State of Kansas, have invented a new and useful Valve-Seating Tool, of which the following is a specification.

This invention relates to tools and more particularly to a reaming tool especially designed for use in reaming valve seats and valve openings.

The primary object of the invention is the provision of a tool of this character wherein the blades may be adjusted to ream valve ports of various sizes.

Another object of the invention is to provide means to prevent lateral movement of the tool while in operation, to insure a true reaming of the valve port.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a side elevational view of a tool constructed in accordance with the present invention.

Figure 2 is a side elevational view of the tool taken at right angles to Figure 1.

Figure 3 is a sectional view taken on line 3—3 of Figure 2.

Figure 4 is a side elevational view of the valve seat reaming blade.

Figure 5 is a plan view thereof.

Figure 6 is an end elevational view of the valve seat reaming blade.

Referring to the drawing in detail, the reference character 5 designates the body portion of the tool which is formed with an enlargement 6 at its lower end, and an enlargement 7' at its upper end.

The enlargement 6 is formed with a relatively large opening 7 extending therethrough, the opening being formed with a

curved lower surface 8 conforming to the curvature of the lower edges of the cutting blades 9 that are positioned therein so that movement of the cutting blades within the supporting opening will be restricted. 55

In order that the blades will be held against movement while in use, an angularly disposed set screw 10 is provided that passes through a suitable threaded opening and has its inner end engaging one of the blades 9 to force the blades laterally within the opening 7, and create a binding action between the blades and one of the side walls of the opening to secure the blades against movement. 65

Formed integral with the body portion and disposed substantially centrally at one end of the body portion is a reduced extension 11 which is of a diameter equal with the diameter of the usual valve stem, whereby 70 the reduced extension may be positioned in the valve stem opening of the usual valve seat of a motor block and rotated, the extension acting as a guide to prevent lateral movement of the tool while in use and insure 75 a true operation of the tool.

The blades as shown, in the tool, and as set forth by Figure 1 of the drawings, are especially designed for reaming the inner wall of the usual valve port, while the blade 80 shown by Figures 4, 5 and 6 of the drawing and indicated by the reference character 12, may be inserted in the openings 7 and employed for reaming the valve seat of the usual valve port. 85

Formed in the enlargement 7' is an opening 13 adapted to receive the rod 14 which may be grasped by the operator to impart the necessary rotary motion to the tool while in use. 90

What I claim as new is:—

A tool including a body portion having an enlargement formed at one end thereof, the enlargement having an opening extending therethrough, overlapping laterally, adjustable blades positioned within the opening and having their cutting edges extending beyond the periphery of the enlargement, a set screw extending into the enlargement and engaging one of the blades for forcing the 100

blades into close engagement with each other and into engagement with one wall of the opening securing the blade within the openings and said set screw being disposed at 5 an oblique angle with respect to the body portion of the tool.

In testimony that I claim the foregoing.

as my own, I have hereto affixed my signature in the presence of two witnesses.

JAMES B. BRYAN.
